REISSUED

UNITED STATES PATENT OFFICE

136,730

DESIGN FOR A CLAMP FOR BLANKETS AND THE LIKE

Rudolph Bernhardt and Jean O. Reinecke, Chicago, Ill., assignors to James F. Barnes, as trustee

Application April 15, 1943, Serial No. 109,974

Term of patent 3½ years

To all whom it may concern:

Be it known that we, Rudolph Bernhardt and Jean O. Reinecke, citizens of the United States, residing at Chicago, county of Cook, and State of Illinois, have invented a new, original, and ornamental Design for a Clamp for Blankets and the like, of which the following is a specification, reference being had to the accompanying drawing forming a part thereof, in which—

Fig. 1 is a perspective view of the device embodying our new design; Fig. 2 is a plan view of the same device; and Fig. 3 is a side elevational view of the same device.

We claim:

The ornamental design for a clamp for blankets and the like, as shown.

RUDOLPH BERNHARDT.
JEAN O. REINECKE.
